FIG. 1

FIG. 2

FIG. 3

FIG. 4

FIG. 5

FIG. 1 is a perspective view of a storage container for lettuce or the like showing my new design, with the cover removed;

FIG. 2 is a similar view with the cover in place;

FIG. 3 is a top plan view of FIG. 1;

FIG. 4 is a bottom plan view of FIG. 1; and

FIG. 5 is an enlarged scale elevational view of FIG. 2. This is a continuation-in-part of my earlier application, Ser. No. D. 906, filed Feb. 3, 1966 now abandoned. I claim:

The ornamental design for a storage container for lettuce or the like, substantially as shown and described.
